ATTORNEY

UNITED STATES PATENT OFFICE.

SAMUEL CUMMINS, OF CHICAGO, ILLINOIS.

PERFORATED SOAP CAKE.

Application filed December 14, 1921. Serial No. 522,275.

To all whom it may concern:

Be it known that I, SAMUEL CUMMINS, a citizen of the United States, and resident of Hotel Ambassador, Chicago, in the county of Cook and State of Illinois, have invented certain new and useful Perforated Soap Cakes, of which the following is a specification.

The purpose of this invention is to provide a cake of hand or toilet soap with means by which it may be anchored and secured against surreptitious pilfering or accidental loss.

A further object is in the provision of toilet soap so shaped as to be conveniently manipulated and comfortably used in an economical way, wear taking place gradually and uniformly in such manner as to retain its original shape and integrity of its fastenings.

These objects are attained by the novel design, construction and arrangement of parts hereinafter described and shown in the accompanying drawing, forming a material part of this disclosure, and in which:—

Figure 1 is a perspective view showing a conventional type of wash stand and illustrating the application of the invention.

Figure 2 is a side elevational view showing a cake of soap made in accordance with the invention, partially broken to indicate the construction.

Figure 3 is a transverse sectional view taken substantially through the center of the soap and its insert.

In the drawing, the numeral 5 designates in general a common form of wash-stand, partially supported by legs 6 and having a bowl 7 into which water may be entered from the faucets 8 and 8'.

An eye 9 is rigidly fixed in or adjacent to the stand and engaged in the eye is a chain or similar flexible element 10, made of material not detrimentally affected by water to which it is obviously frequently subjected.

The cake of soap, generally designated 15, may be of any preferred configuration whatever, as the annulus shown, the same having a band 16 and containing an opening 17 in which is embedded, while molding, a relatively thin, flat washer-like impervious ring 18, made of any desired material as cellu-

loid, fiber, rubber or metal, the same being firmly secured.

Passed through the ring 18 is the bight 55 of the fastener element 10, its end being connected to resist separation by ordinary means, but releasable when a cake of soap is to be substituted for one which has been worn. 60

It will be apparent that in using the soap for toilet purposes, friction and wear takes place on the outer surfaces; the inner surfaces, that is the portions adjacent the central opening, being relatively protected, due 65 to their shape, maintain the inserted securing ring intact.

The advantages possessed by this invention, the characteristic feature of which is a ring embedded in a perforation in the 70 soap bar, will be apparent to those who supply such toilet facilities in places of public or semi-public nature.

While a preferred embodiment of this device has been disclosed, it will be understood that changes in form, proportions and details thereof may be made without departing from the general scope of the invention herein indicated and denoted in the appended claims. 75

Having thus described my invention, what I claim as new and desire to secure by Letters Patent, is:—

1. In combination with a cake of soap designed in the form of an annulus, the inner periphery thereof being provided with a central groove; of an impervious ring seated in the aforesaid groove. 85

2. As a new article of manufacture, a cake of soap having a central opening therethrough, the inner periphery thereof being provided with an annular groove, an impervious ring seated in said groove. 90

3. In combination with a cake of soap designed in the form of an annulus, the inner periphery thereof being provided with a central groove; of an impervious ring seated in the aforesaid groove, the inner periphery of said ring extending beyond the inner periphery of said soap annulus. 95

Signed at Chicago, in the county of Cook and State of Illinois, this 10th day of December, A. D. 1921.

SAMUEL CUMMINS.
